UNITED STATES PATENT OFFICE

165,657

WHEEL COVER OR SIMILAR ARTICLE

George Albert Lyon, Detroit, Mich.

Application March 1, 1950, Serial No. 8,237

Term of patent 14 years

(Cl. D14—30)

To all whom it may concern:

Be it known that I, George Albert Lyon, a citizen of the United States, and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

On the drawing:

Figure 1 is a side elevational view of my novel design for a wheel cover or similar article;

Figure 2 is a profile view showing the cross sectional contour of the cover of Figure 1; and

Figure 3 is a fragmentary side perspective view of the cover.

The dotted lines in Figures 1 and 2 showing the conventional tire and wheel assembly are for illustrative purposes only.

The characteristic feature of my design for a wheel cover is the annular ridge having closely spaced radial indentations, which is positioned intermediately of the hub and the rim portions.

I claim:

The ornamental design for a wheel cover or similar article, substantially as shown and described.

GEORGE ALBERT LYON.
